XEROGRAPHIC DEVELOPING APPARATUS
James J. Grimm and Harold E. Trumbull, Columbus,
Ohio, assignors, by mesne assignments, to Xerox Cor-
poration, a corporation of New York
Filed Dec. 30, 1960, Ser. No. 79,600
6 Claims. (Cl. 118—637)

This invention relates to xerography and, in particular to an improved apparatus for delivering developing material to a xerographic drum. More specifically the invention relates to an improved xerographic developing apparatus to effect cascade development of an electrostatic latent image on a xerographic drum.

In the process of xerography, for example, as disclosed in Carlson Patent 2,297,691, issued October 6, 1962, a xerographic plate comprising a layer of photoconductive insulating material on a conductive backing is given a uniform electric charge over its surface and is then exposed to the subject matter to be reproduced, usually by conventional projection techniques. This exposure discharges the plate areas in accordance with the radiation intensity that reaches them, and thereby creates an electrostatic latent image on or in the photoconductive layer. Development of the latent image is effected with an electrostatically charged, finely-divided material such as an electroscopic powder that is brought into surface contact with the photoconductive layer and is held thereon electrostatically in a pattern corresponding to the electrostatic latent image. Thereafter, the developed xerographic powder image is usually transferred to a support surface to which it can be fixed by any suitable means.

In automatic xerographic machines for the reproduction of copy, it is usual to utilize a constantly moving xerographic plate which may be in the form of a rotating cylindrical drum. By means of a continuously operative developing apparatus a developing material, of a type to be described, is constantly delivered to an upper portion of the drum surface to cascade down over the drum surface and then is retrieved by the developing apparatus. Since electrostatic latent images to be developed are produced on the drum surface in unrelated sequence or with an infinite variety of image configurations, it is important that developing material be presented or delivered to the drum surface at a substantially uniform and adequate rate to effect image development.

Developing material for xerographic development may typically be of a two-component type as disclosed in Walkup Patent 2,638,416. The component materials of Walkup include a suitable pigmented or dyed electroscopic powder hereinafter referred to as "toner" and a granulated bead-like carrier, which later functions to carry and to generate triboelectric charges on the toner. More exactly, the function of the granular material is to provide the mechanical control to the powder, or to carry the powder to an image surface and, simultaneously, to provide almost complete homogeneity of charge polarity. In the development of the image, the toner is attracted to the drum surface in a pattern corresponding to the electrostatic latent image.

Developing apparatus for commercial automatic machines have heretofore been of a general type disclosed in copending application, Serial No. 393,058, filed November 19, 1953, in the name of Mayo et al. Typically this type of apparatus employs an endless conveyor-elevator which includes a plurality of drum-width buckets mounted on timing belts that are driven by specially adapted sprockets. A reservoir in the apparatus is filled with developing material to above the lower level of the buckets so that they are filled passing through the material and are then elevated for delivery of the material to an upper portion of a xerographic drum.

2

Developing apparatus of the belt and bucket type have been successfully utilized in commercial machines. However, because of the inherent structural arrangement of the belt and bucket unit, certain problems have been encountered in their use for which solutions have heretofore not been found. For example, the lower sprockets of the conveyor are operated within the bulk of the developing material and the action of the hard granular carrier beads thereagainst tends to quickly wear the inner surface of the belts which are a major first-cost factor. Also, as the buckets dig into the carrier beads they cause objectionable vibration and unless isolated has a deleterious effect on performing the other steps of the xerographic method that depend upon smooth performance of the apparatus to effect operation. Additionally, the heretofore used apparatus has been known to be relatively noisy and relatively expensive to fabricate.

Any developing apparatus must have an inherent capacity for sufficient storage of developing material and must be capable of delivering an adequate amount of material at a substantially uniform rate. For example, in a typical application in which a drum has a peripheral rate of approximately 4 inches per second, approximately 3 pounds of developing material per minute is required to be delivered per inch of drum width. Therefore, the apparatus should have sufficient storage capacity to continually deliver the required amount. Preferably the apparatus should be of light weight construction, be quiet and substantially vibration free, and should contain and retrieve the material with a minimum of leakage. The apparatus should also provide good mixing between the carrier beads and toner component of the developing material to effect the required triboelectric properties.

Therefore, the principal object of the invention is to improve developing apparatus for delivering developing material to a xerographic drum.

Another object of the invention is to improve developing apparatus for substantially vibration free delivery of developing material to a xerographic drum.

Still another object of the invention is to improve developing apparatus for delivering developing material to a xerographic drum that is less expensive to fabricate than apparatus employed for the same purpose heretofore.

These and other objects of the invention are achieved by the novel developing apparatus of the invention which in the preferred embodiment includes a casing or housing having a wheel supported therein in position adjacent to a xerographic drum and adapted for approximately vertical rotation with its axis arranged substantially at a right angle to the drum axis, a plurality of open buckets for conveying developing material upwardly supported on the wheel around its periphery with the bucket openings disposed toward the wheel axis, and a pair of baffles one of which serves as a slide on which developing material can fall from the substantially inverted position of the upper buckets to the drum surface for cascading thereover and the other of which serves as a slide on which the cascaded material can descend from below the surface of the xerographic drum to the substantially upright position of the lower buckets. Suitable seals are provided for containing the material within the apparatus and a suitable toner dispenser is provided to replenish the developer material with toner consumed in developing.

A preferred embodiment of the invention is illustrated in the accompanying drawings in which:

FIG. 1 is a schematic illustration of a typical xerographic machine incorporating the developing apparatus of the invention;

FIG. 2 is a front elevation of the apparatus of the invention shown with a suitable type toner dispensing

apparatus, and partially broken away to facilitate understanding of its structure;

FIG. 3 is a sectional view taken on line 3—3 of FIG. 2;

FIG. 4 is a sectional elevation taken on line 4—4 of FIG. 2; and,

FIG. 5 is an exploded isometric view of a drive arrangement to effect operation of both the apparatus of the invention and a type of toner dispenser which may be used in conjunction therewith.

General

For a general understanding of the xerographic processing system in which the invention is incorporated, reference is had to FIG. 1 in which the various system components are schematically illustrated. As in all xerographic systems based on the concept disclosed in the above-cited Carlson patent, a radiation image of copy to be reproduced is projected onto the sensitized surface of a xerographic plate to form an electrostatic latent image thereon. Thereafter, the electrostatic latent image is developed with an oppositely charged developing material to form a xerographic powder image, corresponding to the electrostatic latent image, on the plate surface. The powder image is then usually transferred to a support surface to which it is fused by any suitable form of fusing device, whereby the powder image is caused permanently to adhere to the support surface.

The xerographic apparatus described herein typically may be of the type disclosed in the copending application, Serial No. 837,173, filed August 31, 1959, in the name of Cerasani et al. As in the apparatus thereof, original copy is placed on a support tray 10 from which it is fed onto an endless conveyor 11 driven by motor 12. The conveyor moves the original past the optical axis of projection lens system 14 that is illuminated by a projection lamp LMP-1. The image of the original is reflected by mirror 15 through an adjustable objective lens 16, and then reflected by mirror 17 downwardly through a variable slit aperture assembly 18 onto the surface of a xerographic plate in the form of drum 19.

Xerographic drum 19 includes a cylindrical member mounted in suitable bearings in the frame of the machine and is driven in a clockwise direction by a motor 24 at a constant rate that is proportional to the transport rate of the original copy, whereby the peripheral rate of the drum surface is identical to the rate of movement of the reflected radiation image. The drum surface comprises a layer of photoconductive material on a conductive backing that is sensitized prior to exposure by means of a screened corona generating device 25, which may be of the type disclosed in Walkup Patent 2,777,957, that is energized from a suitable high potential source (not shown).

The exposure of the drum to the radiation image discharges the photoconductive layer in the areas struck by radiation, whereby there remains on the drum a latent electrostatic image in image configuration corresponding to the radiation image projected from the original. As the drum surface continues its movement, the electrostatic latent image passes through a developing station 26 in which a two-component developing material 27, which may be of the type disclosed in the above-cited Walkup Patent 2,638,416, is cascaded over the drum surface by means of the developing apparatus generally designated 28, constructed in accordance with the invention.

After developing, the xerographic powder image passes a discharge station 41 at which the drum surface is illuminated by a lamp LMP-2, whereby residual charges on the non-image areas of the drum surface are completely discharged. Thereafter, the powder image passes through an image transfer station 42 at which the powder image is electrostatically transferred to a support surface web 43 by means of a second corona generating device 44 similar to corona charging device 25.

The support surface to which the powder image is transferred may be of any convenient type, such as paper, and is fed from a supply roll 45 over guide rolls 46 and 47, being directed into surface contact with the drum in the immediate vicinity of transfer corona generating device 44. After transfer, the support surface is separated from the drum surface and guided through a suitable fusing apparatus 48 which may be of the type disclosed in Crumrine Patent 2,852,651, whereby the powder image is permanently affixed to the support surface. Thereafter, the support surface is fed over a system of guide and tensioning rolls 49 onto a take-up roll 52 that is driven by means of motor 53.

After separation of the support surface from the drum, a corona generating device 54, which may be of the type described in copending application, Serial No. 845,482, filed October 9, 1959, in the name of Vyverberg, directs a negative charge to a residual powder image on the drum surface and to the support surface before leaving guide roll 47.

Thereafter, the xerographic drum surface passes through a cleaning station 55 at which its surface is brushed by a cleaning brush assembly 56, which includes a pair of brushes 59 and 60 rotated by a motor 57, whereby residual developing material remaining on the drum is removed. Thereafter, the drum surface passes through a second discharge station 58 at which it is illuminated by a fluorescent lamp LMP-3, whereby the drum surface in this region is completely flooded with light to remove any electrostatic charge that may remain thereon. Suitable light traps (not shown) are provided in the system to prevent any light rays from reaching the drum surface, other than the projected image, during the period of drum travel immediately prior to sensitization by corona generating device 25 until after the drum surface is completely passed through the developing station 26.

Developing Apparatus

Referring now to the subject matter of the invention, the developer apparatus 28 includes a cylindrical housing having a peripheral wall portion 71, a rear wall portion 69 and a removable front wall 70 suitably fastened to the peripheral wall portion 71. Secured to the front wall 70, as by welding, are a pair of side walls 74 positioned in spaced-apart parallel relation to each other, a top wall 72 having a depending wall portion 78 secured thereon, and a bottom wall 107.

As shown in FIG. 4, the side walls 74 are formed with a concave edge portion in conformity with the shape of the xerographic drum to permit the developing housing to be positioned closely adjacent to the xerographic drum. Suitably secured to the outer faces of the side walls are a pair of seal holders 77 (see FIG. 3), also formed to conform with the shape of the drum, to support seals 75, preferably made of a self-lubricating material, and a resilient back support 76. The seals contact the outer peripheral edges of the drum to form a powder tight seal between the developer assembly and the xerographic drum. Secured to the top wall 72 is a gasket 73 adapted to operate with the enclosure (not shown) for the optical assembly of the machine to shield the drum from extraneous light.

For containing and delivering developer material to the xerographic drum, there is provided a wheel type conveyor including a circular disc 64 with a peripheral shell portion 83 formed integral therewith, and partly enclosed by annular ring 65. The wheel-type conveyor laterally extending vanes 66 suitably secured thereon, as by welding, forming open ended buckets for conveying developer material to the top of the developer housing.

For supporting the wheel conveyor assembly for rotation within the housing, there is provided a flanged bearing support 92 secured to the rear wall 69 of the developer housing. The flanged bearing support extending through a suitable opening formed in the housing.

As seen in FIG. 4 the wheel conveyor is supported for rotation by a flanged hub 83 secured thereto and to one end of sleeve 89 that is journaled for rotation in the flanged bearings 93 positioned in the flanged bearing support. A suitable packing 94 is provided between these bearings. The wheel conveyor is maintained in axial alignment and is driven by spur gear 122 secured to the opposite end of sleeve 89.

The wheel conveyor is driven by means of motor 110 operatively connected to drive shaft 120 by means of chain 117 which runs on sprockets 116 and 119 fixedly mounted on the shaft of motor 110 and to one end of drive shaft 120, respectively. The motor 110, mounted by means of bracket 144 to the housing 63, is connected to a source of electric power and is controlled by switching means (not shown). Drive shaft 120 is suitably journaled and held in axial alignment in rear wall 69, and carries intermediate its ends a pinion gear 121 which meshes with the spur gear 122 to drive the wheel conveyor.

With a charge of developer material in the conveyor, the wheel-type conveyor is rotated and the developing material begins spilling. The first spillage is baffled by carrier ring 103, secured to the toner dispenser and described in detail hereinafter, so as to cascade the spilled material over the toner dispenser into the lower buckets. Developing material which is further elevated ultimately spills into slide hopper or chute 104 secured to side wall 74 and while gravitating down effects mixing and tribo-electrification between the toner and carrier particles which then pass through a preset opening 105 formed between the hopper and the shield section 78 of the housing. The opening 105 is of a dimension to pass a requisite quantity of material and also to produce some backup accumulation and thereby effect substantially uniform discharge of material across the axial width of the drum.

Thereafter, the developing material cascades down over the drum surface until being diverted by a return baffle 106 onto return or bottom wall baffle 107 upon which the material descends into the buckets below. With the wheel in constant rotation there is constant delivery of developing material to above the hopper which through opening 105 effects uniform delivery to the xerographic drum.

In a typical developing apparatus constructed in accordance with the invention and operated with a drum of approximately 4 inch diameter and 8 inch width, it was found that 35-40 pounds of developing material could be delivered per minute to the drum by employing an 11 $\frac{1}{4}$ inch diameter wheel, 1 $\frac{1}{2}$ inches wide, having 36 buckets, 1 inch deep. Delivery was effected by rotating the wheel at approximately 48-52 r.p.m. when loaded with an initial charge of 1 $\frac{1}{2}$ -2 pounds of material. The material passed through an opening 105 of approximately $\frac{3}{16}$ inch wide and the entire apparatus was inclined toward the drum at approximately 6-10 degrees from the vertical. Obviously the above values are typical and not be considered as limiting as various combinations of speed and dimension will produce the required rate of delivery for any particular application.

Dispensing Apparatus

As the developing mixture is cascaded over the xerographic drum, toner particles are pulled away from the carrier and deposited on the drum to form powder images, while the partly denuded carrier particles pass off the drum into the reservoir. As toner powder images are formed, additional toner particles must be supplied to the developing mixture in proportion to the amount of toner deposited on the drum. To supply additional toner particles to the developing mixture, a toner dispenser 85 is used to accurately meter toner to the developer mixture.

Although any one of a number of well-known powder or granulated material dispensers may be used, the toner

dispenser shown is of the type disclosed in copending application, Serial No. 79,702, filed concurrently herewith on December 30, 1960.

Referring now to the drawings the toner dispensing apparatus 85 includes a frusto-conical or cup-shaped reservoir 113 for the containment of toner material 112 to be dispensed and which is simply constructed and may, for example, be made of sheet metal stampings. The reservoir conveniently is shaped as the frustum of a cone and is mounted for rotation on horizontal shaft 84.

The reservoir is formed of a front section 96 and a rear wall 97 which is contiguously held, except as separated by disc 114, to the front section by means of brace 98 and screws 99 so as to provide a substantially powder tight enclosure therebetween.

For adding toner to the reservoir, there is provided a loading door 123 which pivots about hinges 124 secured to the front of the reservoir and is maintained in a closed position by resilient detent means 125. A plurality of keyslots 127 are provided whereby the drum can be rotated by an operator to place the door into an upright position before opening.

Dispensing is effected by means of a rotatable disk 114 which is supported to force a localized opening between front section 96 and rear wall 97 to produce localized opening. The disk may be plain or toothed and is journaled for rotation on a bent stub shaft 115 secured, as by welding, to bottom wall 107. In the embodiment shown, the disk is approximately 2 inches in diameter and .005 inch wide and as the reservoir rotates the disk is forced to rotate about its own fixed center by friction with the rear wall 97 and the open edge of front section 96.

The disk is located below the rotational axis of the reservoir and provides a fairly uniform slot opening at a point where dispensing occurs. Rotation of the disk effects a shearing action on the toner to keep it well mixed and also prevents toner bridging or agglomerating at the slot opening.

The rate of dispensing by means of the apparatus of the invention is primarily a function of the rotational rate of the reservoir although it is known that ambient conditions of temperature and humidity above standard atmosphere affect the powder in a manner to impede dispensing. However, in conventional operational ranges this affect can be compensated for by variations in the rotational rate.

Rotation of the reservoir is effected from motor 110 which drives sprocket 116 and through chain 117 drives sprocket 118 mounted on shaft 145 suitably journaled in rear wall 69. Through pin 129 rotatably secured to the side face of sprocket 118 and to arm 130, the arm 130 moves eccentrically as sprocket 118 is rotated. Movement of the arm 130 is transmitted as a cranking motion to plate 131, pivotally supported at one end on shaft 84, through pin 132 to move pawl 133 in an oscillatory motion. Pawl 133 is secured to pin 141 which is rotatably secured to the end of plate 131 and is normally biased into driving engagement with ratchet 134 by means of spring 139. With each forward movement the pawl engages a tooth of ratchet 134 to effect its rotation and through which is rotated shaft 84 to which the dispensing apparatus is secured.

Referring to FIGS. 4 and 5, shaft 84, carrying ratchet 134 fixed thereon, is journaled for rotation with respect to sleeve 89 by means of flanged bearings 90 positioned within the sleeve. A packing 91 being inserted between the bearings 90. The reservoir is secured to the front end of shaft 84 by means of hub 146 secured to the inner face of brace 98. Attached to the opposite end of the shaft 84 is a collar 142 positioned to maintain the plate 131 in alignment on the shaft.

The rate of reservoir rotation is controlled by controlling the angle of movement effected with each forward movement of the pawl. Control of the angle is effected

by means of a segmental gear 135 supported loosely on shaft 84 which has a cam 136 extending therefrom to cover a toothed portion of ratchet 134. By means of handknob 137, connected to shaft 143 carrying worm gear 138 which meshes with gear 135, cam 136 is indexed to expose the ratchet tooth on which the pawl in its forward stroke first engages the ratchet. The pawl is urged downward by spring 139 so as to successively ride the cam and then engage the ratchet. When the pawl engages the ratchet at the beginning of its forward stroke 10 maximum rotation of the reservoir is effected, whereas pawl engagement with the ratchet near the end of stroke effects a minimum rotation of the reservoir. However, the absolute rates, i.e., the rotational displacement per unit of time differs by the relative angles of displacement after pawl engagement. As the reservoir rotates, disk 114 rotates simultaneously therewith and it has been found that in addition to dispensing through the localized opening provided by the disk a minute amount of toner is carried and dispensed from the disk periphery.

Since the dispenser provided a uniform dispensing rate per unit of rotation, obviously other means such as a variable speed motor could be provided to vary the rotational rate. As another alternative, different rates of dispensing uniformity can be effected by varying the dispensing opening as by movable wedge shaped disks or by using interchangeable disks of different dimensions.

Operation

In operation, xerographic drum 19 is constantly rotated and an electrostatic latent image formed thereon passes through developing station 26 for developing the latent image by cascading a developing material thereover. Developing material is delivered to the drum for cascading by means of the improved developing apparatus 28 of the invention. In the developing apparatus, a supply of developing material is contained in the lower buckets. As the wheel rotates, the buckets containing the material are elevated until inverting and spilling the material onto slide-hopper 104. On the hopper the material descends through opening 105 onto the drum to cascade thereover. The cascaded material is thereafter retrieved by means of baffles 106 and 107 which deflect the falling material into the upright buckets below. The cycle is continuous.

Toner consumed in the formation of powder images is replenished by means of dispensing apparatus 85. Dispensing is effected from a reservoir 113 through a localized opening provided in the reservoir by a rotatable dispensing disk 114 and is achieved by rotating the reservoir. The dispensing rate can be regulated by means of a rotatable cam 136 which changes the number of teeth in ratchet 134 picked up by constantly oscillating pawl 133 and varies the speed of the dispenser and consequently the dispensing rate.

By the apparatus above described there is disclosed a wheel type conveyor-elevator developing apparatus for delivering developing material to a xerographic drum. The apparatus effects the required delivery and yet it is apparent that it is of simpler construction than apparatus employed heretofore. It has been found that fabrication cost of the present apparatus is approximately 55 percent of the previously used belt and bucket type mentioned above. The unit operates quietly and with a minimum of vibration.

Since many changes could be made in the above construction and many apparently widely different embodiments of this invention could be made without departing from the scope thereof, it is intended that all matter contained in the drawings shall be interpreted as illustrative and not in a limiting sense.

What is claimed is:

1. Apparatus for delivery of developing material to the peripheral surface of a xerographic drum, said apparatus including a housing supported adjacent a drum surface to a portion of which developing material is to be

delivered, a wheel conveyor journaled for rotation in said housing, said wheel conveyor being adapted to contain all of the material internally that is supplied to said drum surface and being mounted for rotation about an axis substantially perpendicular to the drum axis, said wheel conveyor having a plurality of open buckets capable of containing developing material, said buckets being supported on said wheel conveyor and arranged substantially concentric about the wheel conveyor axis with said bucket openings disposed radially to the axis of rotation of said wheel conveyor, means to rotate said wheel conveyor whereby material contained in the lower of said buckets is elevated from below to above said portion of the drum surface, a slide to convey developing material from the upper of said buckets to the drum surface to cascade thereover, means on said housing cooperable with said slide for controlling the flow of material across the axial width of the drum, and said housing having means to convey cascaded developing material from below the drum surface to the lower of said buckets.

2. The apparatus of claim 1 in which said wheel conveyor is positioned for rotation substantially in a vertical plane.

3. The apparatus of claim 1 in which said wheel conveyor is positioned for rotation in a plane inclined from the vertical.

4. Apparatus for delivery of developer material to a portion of the periphery of a rotating xerographic drum, said apparatus including a housing supported adjacent the periphery of a rotating xerographic drum to which developer material is to be delivered, a wheel conveyor mounted in said housing, said wheel conveyor being adapted to contain all of the material internally that is supplied to said drum surface and being mounted for rotation about an axis substantially perpendicular to the drum axis, and including a plurality of open buckets for containing developer material, said buckets being supported in the wheel conveyor with the bucket openings disposed radially to said wheel conveyor axis, means to rotate said wheel whereby developer material contained in the lower of said buckets is elevated from below to above said portion of the drum surface, means to convey developer material from the upper of said buckets to the drum periphery to cascade thereover, means on said housing cooperable with said means to convey developer material for controlling the flow of material across the axial width of the drum, and means to convey cascaded developer material from below the drum periphery to the lower of said buckets.

5. Apparatus for delivery of a developer material to a portion of the periphery of a xerographic drum being rotated about a substantially horizontal axis, said apparatus including the combination of a housing, a wheel supported in said housing adjacent the periphery of a rotating xerographic drum to which the material is to be delivered, said wheel being adapted to contain all of the material internally that is supplied to said drum surface and being mounted for rotation about an axis substantially perpendicular to the drum axis, a plurality of open buckets capable of containing developer material, said buckets being supported on said wheel with said bucket openings disposed radially to the axis of said wheel, means to rotate said wheel whereby developer material contained in the lower of said buckets is elevated from below to above said portion of the drum surface, a first baffle means on which developer material descends from the upper of said buckets to the periphery of the drum to cascade thereover, means on said housing cooperable with said first baffle means for controlling the flow of material across the axial width of the drum, and second baffle means on which cascaded developer material from below the drum periphery descends to the lower buckets.

6. Apparatus for delivery of developer material to a portion of the periphery of a rotating xerographic drum, said apparatus including the combination of a casing, a

wheel supported in said casing adjacent the periphery of a rotating xerographic drum to which developer material is to be delivered, said wheel being adapted to contain all of the material internally that is supplied to said drum surface and being mounted for rotation about an axis substantially perpendicular to the drum axis, a plurality of open buckets capable of containing developer material, said buckets being supported on said wheel and arranged with said bucket openings disposed radially toward said wheel axis, means to rotate said wheel whereby developer material contained in the lower of said buckets is elevated from below to above said portion of the drum surface, first baffle means on which developer material descends from the upper of said buckets to the periphery of the drum to cascade thereover, means on

5

5 to the lower of said buckets, and shielding means ex-

tending to the drum periphery.

said housing cooperable with said first baffle means for controlling the flow of material across the axial width of the drum, second baffle means on which cascaded developer material from below the drum periphery descends to the lower of said buckets, and shielding means ex-

tending to the drum periphery.
